In Canada November 14, 1945

Term of patent 7 years

(Cl. D34—5)

To all whom it may concern:

Be it known that I, Mortimer M. Kastner, a subject of the King of Great Britain and resident of the city of Montreal, in the Province of Quebec, and Dominion of Canada, have invented a new, original, and ornamental Design for a Game Board, of which the following is a specification, reference being had to the accompanying drawing, forming a part thereof.

In the accompanying drawing:

The single figure is a plan view of a game board showing my new design.

The game board herein shown is of conventional thickness.

I claim:

The ornamental design for a game board, as shown and described.

MORTIMER M. KASTNER.
